poration of Alabama

Application September 12, 1936, Serial No. 100,520

7 Claims. (Cl. 34—24)

Wood veneers are produced from logs by peeling the veneer's from the logs while the latter are saturated with moisture, that is, while the logs are soaking wet. The veneers must then be dried until the moisture content is greatly reduced. In drying, the wood shrinks across the grain; apparently no appreciable shrinking taking place until the moisture content has been reduced to about 21 percent, and the shrinkage thereafter occurring, roughly speaking, at the rate of about one-third of one percent of the width of the sheet for each reduction of one percent in the moisture content. Thus, assuming a sheet of veneer to have a width of 100 inches across the grain and to contain moisture in excess of 21 percent, no appreciable shrinkage, during drying, occurs, until the moisture content has been reduced to about 21 percent. If the drying of the veneer be then continued, it gradually shrinks. If the drying is carried out until the moisture content is reduced to 6 percent, for example, the shrinkage amounts to approximately 5 inches, so that the sheet is now only 95 inches wide. Veneers may be air dried or dried in kilns. The drying of veneers so that they will remain flat and will not split or check, except by comparatively expensive processes, has always been difficult, and so far as I know, no satisfactory solution of the problem has heretofore been found. If a sheet of veneer be held fast while it is drying, it cannot contract and will split. This is a condition encountered when the drying is done in stack formation with spacing strips between veneers. There is also likely to be uneven drying of the veneers due to the more ready access of the drying air to some parts thereof than to other parts, whereby one or more areas may be dried and should therefore have shrunk the requisite amount, whereas natural shrinking is prevented, by the presence of adjacent areas or sections that are still relatively wet. Drying in the usual way leaves the veneer in a more or less distorted condition, instead of flat, thereby making the laying up of veneers in the manufacture of plywood more difficult than if the veneers were flat; and it also produces considerable variations in the width of a sheet of veneer at different points throughout the length of the sheet, necessitating trimming of the veneer before it becomes part of a panel assembly. There are often large knots in sheets of veneer which, while rendering the veneer unsuitable for use as facing plies, are not objectionable when appearing in interior or core plies. However, in ordinary drying, these knots often become loose and fall

out. In that case, strips each at least as wide as a knot hole and extending across the entire length of the sheet must be cut out of the sheets to permit them to be used even as interior plies. This occasions waste of material and added expense in the manufacture of the veneers themselves, and necessitates the assembling and tapping together of a plurality of narrow pieces of veneer, instead of a single wide sheet, in making an assembly of veneers for a plywood panel. In short, the problem of successfully drying large quantities of veneer at a low cost has been so serious as to constitute an important factor militating against the feasibility of commercially producing thick inexpensive plywood panels.

The object of the present invention is to make it possible to dry large numbers of large sheets of wood veneers at a low cost, and in such a manner that each sheet remains flat, of approximately uniform width throughout its length, without loose knots if there be knots in the sheet and, generally, in a sound condition.

In carrying out my invention I dry the veneer while it is unconstrained, although it may be lightly held in a flattened condition, and while exposing to the drying air a surface area which, for all practical purposes, comprises the total area of its two faces; so that my invention may be viewed in one of its aspects as comprising a novel process whereby large sheets of wood veneer are caused to dry in a natural manner.

It is not sufficient that the veneer be somehow held in a flattened condition with its broad faces exposed to a drying medium, but the veneer must be supported in such a manner that no forces are set up, during shrinking, that produce the difficulties above noted. I therefore stand the veneer on edge, with the grain extending horizontally. Then, when the veneer shrinks, it is in the vertical direction. If, during the drying, the veneer is not constrained, so that the effect of gravity may be utilized, the contraction will be entirely in the downward direction; the lower edge of a sheet of veneer remaining stationary and spaced points along a vertical line moving downwardly through distances varying directly with their respective distances from the lower edge of the sheet. During drying, gravity actually exists in the prevention of cracking, because it is always acting in the direction in which movement of the wood must occur, during shrinking, if no cracks are to open.

Veneers will not stand upright of their own accord. In peeling and slicing veneers from the log or flitch, the cutting is done by means of

knives which make sharp bends in the veneers as the latter leave the log or flitch. This tends to fracture the wood on the side next to the log. This results in a weakening of the veneers on one side, so that they will bend more easily in one direction across the grain than in the opposite direction. In other words, knife-cut veneers, which are the veneers to which this invention relates, will not of themselves stand on edge like a board of the type known as lumber, and they cannot be clamped in upright positions because they will tear under the shrinking stresses.

Therefore, viewed in one of its aspects, the present invention has for its object to make it possible effectively to support knife-cut wood veneers in upright position, with the grain extending horizontally and so nearly unconstrained that they are compelled to settle under the action of gravity when subjected to currents of drying air or the like that sweep over their broad faces.

In order that the cost may be kept low, it is necessary that the manner of handling the veneers up to the time that they are dried and, preferably, up to the time that a preliminary or other gluing of veneers into panels, must be such that little labor is required and that no appreciable breakage of veneers will result. Therefore, viewed in certain of its aspects, the present invention may be said to have for its object to produce a simple and novel method of drying and handling large sheets of wood veneer up to the point where gluing operations are to begin; and, also, simple and novel apparatus by which my new method is made possible or, at least, is greatly facilitated.

In carrying out my invention, I provide numerous panel-like racks, so devised that when two of them are placed together, they form a wide, high, shallow cage in which a single piece of veneer may be contained in a substantially flat condition. Drying air therefore has ready access to all parts of the superficial area of each sheet of veneer. These racks are stood upright, each pair in contact with adjacent pairs on opposite sides thereof. The veneers are so placed in the cages that the grain is substantially horizontal, and the drying air is caused to flow in the vertical direction across both faces of each sheet. With this arrangement, if the drying be not uniform throughout the height of a sheet standing on edge, no splitting or checking results, because the moisture content will usually be approximately uniform across the entire horizontal length or width of the sheet for any given elevation above the lower edge of the sheet. Consequently, since the grain of the wood is horizontal, somewhat uneven drying does not result in splitting or checking of the veneer. Trucks, each adapted to carry and transport a large number of pairs of racks, standing on edge, are preferably provided; provision being made to permit the racks to be swung about their lower edges through small angles, in the manner of the leaves of a book. A truck full of racks may be filled with veneers by simply wheeling the truck under the end of a conveyor or slide from which sheets of veneer may be dropped edgewise into open cages ready to receive them. In other words, the first pair of racks are swung apart somewhat at their upper ends to provide an inlet into which a sheet of veneer may easily be inserted. The innermost of the two racks of the first pair is then swung over in closed relation to its mate, the first rack, leaving a top opening between the inner rack of the first pair and the next rack.

The second sheet is deposited in this second opening, and the third rack is then swung over against the second, providing a top opening between the third and fourth racks. The truck is edged along, as conditions require, to facilitate the insertion of veneer sheets between each adjacent pair of racks of the entire group or series.

Therefore, viewed in one of its aspects, the present invention may be said to have for its object to produce a simple and novel open-work container adapted to house a single large sheet of wood veneer in such a manner that air or other gaseous drying medium caused to flow along opposed sides of the container will effectively reach all parts of the faces of the sheet of veneer located therein.

A series of loaded trucks may be wheeled into a suitable tunnel-like dryer so equipped that when heated air is forced in at one end, it will zigzag up and down through the veneers, finally passing out at the opposite end of the tunnel. By properly regulating the conditions, the veneers may be effectively dried without splitting or checking.

Upon removal of the trucks from the dryer, each truck may be unloaded, the veneers being placed in stacks or bundles and the racks transferred to an empty truck, if desired, which latter truck is then ready to receive a new charge of veneers to be dried. At the time of removing the dried veneers from a truck, they may be sorted, according to grade or quality, so that no further handling of individual sheets will be required until individual veneers are assembled as one of the steps in the production of a plywood panel.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a vertical longitudinal section through a drying kiln, showing more or less diagrammatically one type of kiln construction and a row of loaded trucks filling the same; Fig. 2 is a section on line 2-2 of Fig. 1; Fig. 3 is an elevational view of one of the open-work racks, sections extending transversely of the same being omitted to shorten the height of the view; Fig. 4 is an edge view of the rack, on the same scale as Fig. 3; Fig. 5 is an edge view of two racks placed together with a sheet of wood veneer positioned between the same, only upper and lower fragments of the assembly being illustrated; Fig. 6 is a perspective view of a fragment of a rack composed largely of wood; Fig. 7 is a perspective view of one corner of the rack illustrated in Figs. 3, 4 and 5, on a smaller scale than Fig. 5; Fig. 8 is a view similar to Fig. 7, showing a much smaller fragment, and illustrating a means for temporarily clamping a sheet of veneer to the rack; Fig. 9 is a diagrammatic view illustrating a truck loaded with racks or veneer holders which are being filled with veneers from a delivery table; Fig. 10 is a perspective view showing diagrammatically a loaded truck and portable beds or bases in the proper positions to begin unloading of the filled truck and the stacking of veneers in assorted lots; Fig. 11 is a top plan view of one of the trucks, the stakes being omitted at the side which is at the bottom of the drawing; and Figs. 12 and 13 are sections taken respectively on line 12-12 and 13-13 of Fig. 11, all of the stakes being shown.

The present invention depends upon the ability to support many large sheets of wood veneer in a comparatively small space, in a manner to leave the veneers free to contract while supporting them so that heated air may be caused to flow over and come in contact with the entire area of each face of each sheet. This may be accomplished by providing suitable holders such as shown, for example, in Figs. 3-8. Each holder or container consists of two open-work panels which, when placed face to face, are spaced apart a distance slightly greater than the thickness of the veneer to be received thereby. If it be desired to construct these panels or racks from metal, each panel may comprise a series of parallel thin, flat metal bars 1, 1 set on edge and connected by suitable transverse pieces. In the arrangement shown, the bars are connected together by cross wires 2, 2 welded to the bars. In an actual panel that may be 6 or more feet wide and perhaps 10 or more feet high, the bars 1, which are intended to be vertical in the ordinary use of the panels, may be of steel, about three-quarters of an inch wide and one-twentieth 25 of an inch thick, the spacing between the bars being about a foot. The spacing between the wires in such a construction may be less than that between the bars. The two bars at the sides of the panel may be stiffened, each by a flat bar 3 set on edge against the outer face of the side bar and welded to the latter; each side bar thus being, in effect, a T-bar. Each panel or rack has thereon two spacing elements 4 and 5 extending across the entire width thereof from one side bar to the other and welded to both side bars and to the intermediate vertical bars; the spacing element 4 being on one face close to the top of the rack and the element 5 being on the opposite face or side of the rack and close to the bottom. Therefore, when two of these racks are placed together, face to face, they are held apart a distance equal to the thickness of the spacing elements or bars which then form top and bottom walls for a shallow chamber extending throughout the width and almost throughout the entire height of the assembled racks. If the veneer to be dried is about one-seventh of an inch thick, the spacing bars or elements may be about a quarter of an inch thick, so that when a sheet of veneer, such as indicated at A in Fig. 5, is placed in the chamber between two racks, it is not gripped or clamped and, at the same time, is held upright and must remain substantially flat. The veneer is placed with the grain of the wood running crosswise of the rack, namely horizontally, so that end grain appears in the vertical edges as indicated in Fig. 5.

It will be seen that because the vertical bars 1 are very thin, they could not cover any substantial surface area of a sheet of veneer even if in contact therewith throughout their lengths. However, the contact between the veneer and the bars of the cage in which the veneer finds itself is at distributed points only, so that the total surface area actually covered by the bars is negligible. Also, the open-work construction just described does not interfere to any appreciable extent with effective contact between currents of drying air flowing past a pair of operating racks in the general plane of the latter and the sheet of veneer lying between the racks.

If desired, each sheet of veneer may be clipped lightly to one of the racks between which it lies, thereby to facilitate the subsequent handling of the veneer. This will usually not be done until

just prior to removing the dried sheet from between its racks. Thus, in Fig. 8 I have illustrated a clip 6 in the form of a strip of flat spring metal bent into U-shape; the size of the clip being such that it may embrace one of the edge flanges 3 of the rack and an adjacent marginal portion of the piece of veneer A. Several narrow clips or a clip that is made from a long strip folded along a longitudinal line may be employed. When the veneer is clipped to a rack, the veneer will be carried along with the rack when the latter is swung from a vertical into a horizontal position, instead of collapsing as might otherwise be the case.

The racks may of course be constructed in a variety of ways. In Fig. 6, for example, there is illustrated a fragment of a rack in which the vertical bars 7 and the transverse spacing bars 8 are composed of wood; the vertical bars being tied together with cross wires 9, corresponding 20 to the wires 2 in the other construction. The upright bars are also shown as comprising two half-bars lying flat on each other and secured together. This permits the wires to be laid against one set of half-bars and to be secured 25 when the other set of half-bars are laid on and fastened to their mates. The upright bars are provided on the sides thereof with simple contact devices which are adapted to press lightly against the veneer and hold it so that it will not lie flat 30 against the faces of the vertical bars which may be regarded as comparatively broad even though they may be only an inch or so wide. These contact devices may be simple wires 10 extending longitudinally of the bars and secured thereto at 35 intervals by staples 12 or otherwise. The work is done in such a way that when the staples are driven in, the wires are caused to bow outwardly from one staple to the next and form yieldable contact means holding the veneers spaced apart 40 from the bars proper, without actually covering up any appreciable surface areas on the veneers.

Veneers to be dried are preferably inserted in racks already in position on a truck or the like, thereby facilitating and simplifying the handling 45 of the veneers and racks and making it unnecessary to handle individual units again until after the drying has been completed. In Figs. 11-13, there is illustrated a simple form of truck suitable for my purpose. The truck comprises a low open-work bed or body on which the racks may be stood on edge, and which permits air to pass vertically through the same and over the surfaces of the veneers thereon. In the arrangement shown, the body of the truck consists of a rectangular wooden 55 frame 13 spanned by a series of longitudinal sills 14 and provided with suitable wheels 15. A pair of diagonal brace rods 16 keeps the frame in its rectangular form. The sills 14 are preferably spaced the same distance apart as are the upright 60 bars of the racks, so that when a rack is placed on the truck its upright bars will all rest directly upon the truck sills. To facilitate proper locating of the racks on the truck and prevent accidental lateral displacement sufficient to cause the 65 bars to slip off the sills, some of the sills may have steel strips 17, or thin plates fastened to the sides thereof and projecting slightly above the upper edges of the sills. In the arrangement shown, two of the sills are thus equipped. Consequently, 70 when a rack is to be placed on the truck, the lower ends of two of the upright bars are inserted in the grooves or channels produced by the elements 17 and the rack will thereafter be prevented from shifting too far in the plane thereof.

The truck is shown as having upright stakes 18 at its four corners. The upper ends of the stakes at the front end of the truck are connected together by a cross piece 19 as are also the stakes 5 at the rear. The lower ends of the stakes are fitted into suitable pockets 20, so that they may be lifted out at will. Furthermore, either the stakes or the pockets, or both, are so shaped that when the stakes of either unit are set into the 10 pockets in one position, they stand upright, whereas, upon turning the unit around and inserting the stakes in the pockets, the stakes are caused to be inclined upwardly and outwardly. In the arrangement shown, the lower end of each stake 15 has on one side a face parallel with the length of the stake, and on the opposite side, a face 22 that lies at a small angle to such axis. These are the faces that engage either with the outer surface of the ends of the truck body or with 20 corresponding vertical surfaces in the pockets, and I am thus enabled to cause the stakes to stand upright or in slightly inclined positions.

The trucks are made long enough to receive, say, 50 racks, thereby permitting each truck to 25 be loaded with 49 sheets of veneer. The filling of the racks upon a truck may be accomplished in the manner diagrammatically illustrated in Fig. 9. The masses marked B and C in Fig. 9 are intended to represent two groups of racks, the 30 group B having already received a filling of veneer sheets, while the racks of the group C remain empty. It will be seen that the stakes on the truck are in their inclined positions so that the racks may be swung through limited angles 35 in the manner of the leaves of a book. In order to continue the filling of the racks, beginning at the point to which the filling has proceeded in Fig. 9, I simply insert between the two rack groups B and C a sheet of veneer and then swing the left-hand rack of the group C toward the left and thus 40 form with the righthand rack of the group B a cage in which the sheet of veneer is housed. Another sheet of veneer is then lowered into the gap between the two groups of racks and another rack 45 of the group C is swung over to join the racks of the group B; this process being repeated until all of the racks are filled.

Since the sheets of veneer which are being handled are very large, it is advisable that each 50 sheet be delivered from some overhead support below which the truck may be brought and moved step by step so as always to keep what may be termed the jaw into which the veneer is to descend directly in the path of the descending veneer. In the arrangement shown, the support for the 55 individual sheets of veneer is simply a wide, smooth runway 23, the end of which is curved downwardly on a comparatively large radius. The veneer is fed along this runway, with the grain running crosswise. As the advance edge 60 of the veneer reaches the downwardly curved portion of the runway, its flexibility permits it to follow the curvature of the latter so that when the veneer passes beyond the edge of the runway, it is pointing straight down and may therefore 65 be guided into place on the truck without difficulty.

The veneers are dried while on the truck, as 70 will hereinafter be described, and the truck is then unloaded. The operation of unloading the truck is preferably carried out in such a manner that the sheets of veneer lie in horizontal positions at the time of their removal from the racks. In Fig. 10, there is illustrated the preferred method of unloading. The trucks of course run upon 75

rails because their loads are heavy. Therefore, a truck loaded with racks B filled with dried veneers is run along the rail system 24 to the unloading point, and a second empty truck is brought up close to it. The stakes on the sides 5 of the two trucks that are toward each other are removed. Blocks are placed under the wheels of the trucks, or the trucks are otherwise temporarily secured in such spaced relation to each other that the horizontal distance between the lower end of 10 the first rack on the loaded truck, which is the righthand rack in Fig. 10, is spaced apart from the standing stakes on the empty truck a distance equal to the height of the rack. Therefore, the righthand rack in Fig. 10 may be swung down, 15 its two upper corners describing the arcs represented by the broken lines D, D, until it lies flat on the body of the empty truck. The sheet of veneer between this rack and the next rack in the series is carried along with the first rack during 20 this downward swinging movement. It may be held to the descending rack by the hands of the workman, or it may previously have been clipped to this rack as heretofore explained. In any event, there is now a sheet of veneer lying on the 25 empty truck, and this sheet may be slid off sideways without danger of breaking or otherwise injuring it.

Veneers are not all of equal quality. In manufacturing plywood, even though all of the plies 30 are of the same wood, the outer plies must be of high quality, whereas the inner or core plies may contain imperfections rendering them unsuitable for use as face plies. I therefore place on opposite sides of the track, at the unloading point, a pair 35 of receiving beds or platforms E and F. As the sheet of veneer, which has just been placed in a horizontal position on the empty truck, lies exposed, a glance will suffice to show whether it can be used for faces or whether it is fitted only for 40 use in places where it is concealed by other plies. If the former, it is slid over upon the bed or platform E, or, if the latter, it is placed on the platform F. The righthand truck in Fig. 10 now 45 contains only an empty rack. This rack is then swung up into an upright position of rest against the standing stakes. The second rack of the loaded group may now be swung down, bringing into a horizontal position a second sheet of veneer. This second sheet is then placed on the bed or 50 platform E or F, according to quality thereof, and the empty rack is then stood upright beside the first one. This procedure is followed until the lefthand truck is empty, all of the veneers 55 are stacked on the beds or platforms E and F, and all of the racks are standing upright on the previously empty truck. The missing stakes are then placed in position on the latter truck which 60 is then ready to be rolled to the loading point where other sheets of veneer to be dried are inserted between the racks.

It will be seen that when an assembly of racks and veneers stands upright on a truck, air may be blown or drawn through the assembly in vertical directions, either up or down.

In order to dry the veneers in a reasonably short time, it is not feasible to rely upon the natural atmospheric air currents to effect the drying. Furthermore, in order to prevent buckling of the veneers, the grain of the woods should 70 be approximately horizontal instead of vertical. With this disposition of the grain in the wood, the drying air should move past the sheets in the vertical direction, namely in the direction in which shrinkage of the wood occurs; and, to 75

produce air currents of that type, artificial aids must be provided.

In accordance with my invention, the loaded trucks are rolled into drying chambers or tunnels 5 so designed that when air is blown into one end, it zigzags up and down through the assemblies of veneers and racks as it travels toward and to the opposite end. This drying system is diagrammatically illustrated in Figs. 1 and 2, in 10 which 25 represents a long tunnel-like building, the interior of which is slightly wider than an assembly of racks to be dried, and the height of which is somewhat greater than the overall height of a truck loaded with the tallest racks; veneers 15 peeled from the same length of log being produced in various lengths measured transversely of the grain so that racks of different heights house the various lengths of sheets. The building 25, to which I shall refer as a kiln, stands over 20 a pit 26 extending throughout the entire length of the same and having a width almost as great as that of the kiln. This pit is conveniently produced by excavating the soil between the longitudinal foundation walls 27, 27 for the kiln, and 25 connecting these foundation walls with a horizontal wall 28 that constitutes the floor of the pit. Rails forming part of the track system for the trucks are located on the tops of the two foundation walls 27, 27 within the kiln. The pit 30 is divided into a series of compartments by transverse partitions 29 extending across the depth and width of the same at intervals throughout its entire length. These partitions are so spaced that the distance between centers of adjacent partitions is an even multiple of the length of one of the trucks. Therefore, when the kiln is filled with trucks engaged with each other end to end, and two of the trucks are placed so as to meet directly over one of the partitions, other 35 trucks will meet each other just above every other partition.

In the top of the kiln are gates 31 extending transversely across the entire width of the kiln and hinged to the kiln so that one long edge of 45 each lies close to the roof of the kiln. The width of each gate, measured in a direction at right angles to the hinge axis, is preferably somewhat greater than the distance between the roof of the kiln and the tops of the shortest racks with 50 which a truck may be loaded. Therefore, when loaded trucks are rolled into the kiln, the gates will engage with the tops of the racks along the lower edges of the gates, and will ride on the rack assemblies as the trucks move. Thus, re- 55 gardless of the height of the racks, these gates will always form barriers across the space within the kiln between the roof and the tops of the rack assemblies. Where hinged gates are employed, it is necessary that the trucks always be 60 caused to travel in one direction, since otherwise the gates would be caught in the openings in the top of the rack assemblies and broken. In the arrangement shown, the trucks are intended to enter the kiln at the lefthand end, as viewed 65 in Fig. 1, and leave at the righthand end. The spacing between the gates is the same as that between the partitions 29, and the gates are staggered with respect to the partitions. The kiln may have removable end walls or doors 32 70 and 33. Means are provided to blow air, preferably heated, into one end of the pit. The other end of the pit may be left open, or it may be connected to an air recirculating system, if desired. In the drawings I have illustrated a blower 75 34 adapted to receive heated air through a con-

duit 35 and discharge it into the righthand end of the pit through an outlet member 36 passing through a wall 37 that closes the righthand end of the pit.

In Fig. 1, the kiln is shown long enough to house thirteen trucks engaged end to end. The first partition 29 from the right lies in the vertical plane in which the second and third trucks meet, and each subsequent partition lies three truck lengths to the left of the preceding partition. There are illustrated three gates each of which lies approximately midway between the consecutive partitions. Assuming the conditions to be such as represented in Fig. 1, it will be seen that if air is blown into the righthand end 10 of the pit, it can travel along the pit only until it reaches the first partition 29 and therefore rises through the assemblies in the upper regions of the kiln. Forward movement of the air into the top of the kiln is checked when the 15 first gate is reached and, therefore, the air now flows down through the rack assemblies lying to the left of the first two and to the right of the gate. When the air emerges below the trucks on which are located the assemblies through 20 which the air has traveled in the downward direction, it enters the pit to the left of the first partition 29 and then can again move along the pit, but only until the second transverse partition is reached. The only outlet for the air is 25 now in the upward direction through those rack assemblies lying between the vertical planes of the lower edge of the first gate and the second partition 29. Thus, the air comes back again 30 into the top of the kiln and, as will be readily 35 understood, it then flows alternately down and up until it is finally discharged into the pit beyond the partition at the extreme left of the series of partitions in the pit.

The trucks may be provided with parallel partitions as indicated at 38 in Figs. 11-13; these partitions extending across the entire width of the space between the side or longitudinal members of the frame 13 and at right angles to these members; the partitions reaching from the 40 plane of the lower edge of the frame to the top and preferably to the plane of the upper faces of the sills 14. Therefore, if the trucks are so positioned in tunnel or kiln that the transverse partitions 29 in the pit do not register with 45 the meeting points between trucks as shown in Fig. 1, the partitions 38 in the truck will serve as barriers to prevent the drying air from being blown along the pit across the tops of the partitions in the pit. Otherwise, if the trucks were 50 shifted to the right or left from the positions which they occupy in Fig. 1, there would be but little circulation of drying air through the groups of veneers as the air would find a more direct 55 passage to the air outlet across the tops of the 60 partitions in the pit.

It is believed that the functions of the various features of my invention and the manner of operation of these features which are structural have been sufficiently described in the foregoing part of this specification and therefore require no further description. It will of course be understood that while I have described with great particularity what I believe to be the best 65 mode of carrying out my invention, including specific embodiments of each structural part, I do not desire to be limited to such details; but intend to cover all processes, machines, apparatuses, structures, and devices coming within 70 75

the definitions of my invention constituting the appended claims.

I claim:

- 5 1. The method of drying large sheets of knife-cut wood veneer which consists in inserting each sheet in an open-work container having therein a chamber at least as long and as wide as the sheet and a depth somewhat greater than the thickness of the sheet, holding the container upright with the grain of the wood running horizontally, and causing drying air to flow in the vertical direction past the container in the plane and across both sides thereof.
- 10 2. The method of drying large sheets of knife-cut wood veneer which consists in inserting each sheet in an open-work container having therein a chamber at least as long and as wide as the sheet and of a depth somewhat greater than the thickness of the sheet, placing a series of such filled containers face to face in upright positions, and causing air to flow through the assembly of filled containers parallel to and in contact with the sheets of veneer.
- 15 3. The method of drying large sheets of knife-cut wood veneer which consists in inserting each sheet in an open-work container having therein a chamber at least as long and as wide as the sheet and of a depth somewhat greater than the thickness of the sheet, placing a series of such filled containers face to face in upright positions with the grain of the wood extending horizontally, and causing air to flow vertically through the assembly of filled containers parallel to and in contact with the sheets of veneer.
- 20 4. The method of drying large sheets of knife-cut wood veneer which consists in inserting each sheet in an open-work container having therein a chamber that is at least as long and as wide as the sheet and has a depth somewhat greater than the thickness of the sheet, placing large

numbers of filled containers face to face on carrier means, moving the carrier means into a drying chamber, and causing air to flow through the assembled containers in the planes and past all of the containers.

5 5. The method of drying large sheets of knife-cut wood veneer which consists in lightly holding a considerable number of such sheets near each other in upright positions with the wood grain extending horizontally in such a manner that each sheet while in a flat state is not subjected to any gripping forces sufficient to prevent freedom of movement in contracting, while drying, and without covering any considerable surface area of any sheet, and causing currents of gaseous drying material to flow vertically across both faces of each sheet.

6. The method of drying large sheets of knife-cut wood veneer which consists in lightly holding a considerable number of such sheets near each other in upright positions, with the wood grain extending horizontally, each sheet being positioned between two open-work upright panels without being subjected by the latter to gripping forces that will interfere with the free contraction of the wood in drying, and causing currents of gaseous drying material to flow vertically through the spaces between such panels.

7. The method of drying sheets of knife-cut wood veneer which consists in causing each sheet to stand on edge with the grain running horizontally, lightly constraining each sheet so as to compel it to remain in an upright position and yet compel it to settle freely under the action of gravity at the proper rate to compensate for the natural contraction of the wood in drying, and causing currents of drying gases to flow in the vertical direction past both broad faces of each sheet.
